UNITED STATES PATENT OFFICE.

HARRY YATES, OF HAPEVILLE, GEORGIA, ASSIGNOR TO UNDERWOOD TYPEWRITER COMPANY, OF NEW YORK, N. Y., A CORPORATION OF DELAWARE.

TYPE-WRITING MACHINE.

1,268,062.

Specification of Letters Patent. Patented May 28, 1918.

Application filed August 27, 1917. Serial No. 188,278.

To all whom it may concern:

Be it known that I, HARRY YATES, a citizen of the United States, residing in Hapeville, in the county of Fulton and State of Georgia, have invented certain new and useful Improvements in Type-Writing Machines, of which the following is a specification.

This invention relates to decimal tabulating-key mechanisms of typewriting machines, especially where there is provided a row of tabulating keys for arresting the carriage at different denominational positions, after release thereof for a tabulating or jumping movement.

One of the benefits arising from the use of my invention is that advantage may be taken of the fact that in performing certain kinds of work, the same decimal tabulating key is used most of the time for jumping the carriage. For example, it is found that in some cases the tabulating usually involves the arrest of the carriage at the "hundreds" point.

I provide a special decimal key for frequent operation, which special key is attached to the most frequently used denominational key lever, elevated far above the remaining decimal keys, and is preferably made broad, so that it can be struck by the palm of the hand, so that when the operator desires to use said special key, he needs only to strike the key with the palm of his hand, without taking time to hunt for one key in the row or bank of keys. The time and labor saved by this invention are therefore very great, and errors are minimized. This useful special key does not interfere with the remaining tabulating keys in the bank, for, although the key is made wide, so that it may be readily operated by the palm of the hand, still the widened part is far above the key or keys which it overhangs, so that there is room beneath the widened part for the operator to reach these keys.

Since for different purposes or in the case of different establishments, different decimal keys are most frequently used, I have made my invention preferably in the form of an attachment, whereby it may be used in connection with any selected tabulator key. This attachment is in the form of a palm-piece, constituting a rider, forked to straddle any decimal key and overhang the ordinary key-cap thereon. It may be placed

upon any of the decimal tabulating key levers.

The invention has a further advantage in that it minimizes the time and labor required in skipping columns. Usually, when wishing to skip a column, the operator selects and then depresses the decimal-point key, the carriage being released and arrested thereby; and then he re-depresses said key, to proceed to the next column; this operation being further repeated if there are two columns to be skipped. By using the present invention, the operator needs only to bring his palm down upon the palm-key, and then release it, repeating for each column that is skipped, the necessity for selecting any one key from among many other similar keys in the bank or row, being avoided. The saving of labor and time is considerable where there is much column-skipping to be done.

Other features and advantages will hereinafter appear.

In the accompanying drawings,

Figure 1 is a vertical section taken from front to rear, with parts omitted to simplify the showing.

Fig. 2 is an enlarged detail perspective view, showing the false key on the thousands decimal tabulator-key.

The usual numeral keys 1 and alphabet keys 2 operate type-actions 3 to strike a platen 4, mounted to rotate on a carriage 5. The carriage 5 has the usual step-by-step movement under the control of the escapement mechanism, indicated in general at 6. This escapement mechanism is that used on the standard Underwood typewriting machine, and operates at the depression of any of the keys 1 and 2, to feed the carriage 5 a letter-space or digit-column at a time.

In addition to having step-by-step movement, the carriage 5 may have jump movements in order to move from one major-column or zone to another. For this purpose, there are provided decimal tabulator keys 7, which when depressed, rock key-levers 8 about a pivot 9, so as to raise the rear of these levers. The depression of the tabulator keys 7 thus forces upwardly plungers 10 resting on the key-levers 8, so that they may be projected individually into the path of the stops 11, carried by the carriage 5. The stops 11 are adjustably mounted at letter-space intervals on the rack 12,

carried by the carriage 5. The carriage 5 is released from its escapement mechanism 6 in the usual way at the depression of a key 7 by means of a train of linkages 13, including an arm 14, universal to all of the plungers 10. There may be any number of stops 11 within the capacity of the carriage 5, and according to the number of major columns or zones desired.

10 The tabulating-keys 7 are decimal tabulating, and when depressed, not only jump the carriage 5 to the next computing zone, but also select a particular letter-space or digit-space in that zone. The keys 7 have 15 various designations on their caps, indicating the particular denomination which they select. Any one of these keys will control the jumping from one major-column or zone to the next major-column or zone. If it is 20 desired to skip one zone, that is, not type-write in any particular zone, the carriage must be first jumped to this zone and then jumped to the next succeeding zone. To 25 avoid confusion under such circumstances, it is desirable to always strike one particular key. This enables the movement from zone to zone to be done rapidly. Also where the numbers typewritten in the various major-columns or zones are of substantially the same magnitude, the same key 30 which controls the selection of the highest denomination of the numbers written can be struck repeatedly for the several zones or major-columns.

35 In order to make one of the decimal-tabulator keys 7 more prominent than the others, and more easily operated for the purposes just mentioned, a false key 15 is provided, which may be adjusted to any one of 40 the key-levers 8. This false key 15 is in the form of a rider, and is bifurcated at its lower end by means of a slot 16 so as to tightly straddle one of the key-levers 8. At 45 its upper end the false key 15 projects forwardly so as to overhang the key cap of the associated decimal-tabulator key. Thus, the false key 15 forms an extension for the particular tabulator-key 7 with which it is associated, enabling this key to be operated 50 more easily than would be the case if operated by striking its key cap, which is located in close proximity to the key caps of the next adjacent tabulating-keys.

It will be noted that the shank of the false 55 key 15 is thin intermediate its ends so as to extend between the key cap of the key 7 and the frame 17 of the typewriting machine.

At its upper end where it bends to overhang the key cap, the false key 15 is thickened so 60 as to give the necessary strength.

Thus, it will be seen that a simple device

is provided for making any one of the decimal tabulator-keys more prominent than the rest, or at least enabling it to be more easily operated than would otherwise be the case. 65 In this way where tabulating is desired without much decimal selection, the work can be done rapidly without too much thought or consideration on the part of the operator. 70

Variations may be resorted to within the scope of the invention, and portions of the improvements may be used without others.

Having thus described my invention, I claim:

1. The combination with a series of closely-nested keys having striking surfaces in close proximity and in alinement with each other, of a false key for making one of said series of keys more accessible, said 80 false key supported below the striking surface of the key with which it is associated and extending to a projected position above the striking surface of such associated key. 85

2. The combination with a series of closely-nested keys including key-levers and key-caps affording striking surfaces in close proximity to each other, of a false key arranged to selectively ride on any of said key-levers having a bifurcated shank straddling the key-lever with which it is associated and having an overhang to project over the key-cap of the key with which it is associated on a level considerably above the striking level of said series of keys. 95

3. In a decimal-tabulating mechanism, the combination with a carriage and decimal stops therefor, of carriage-releasing mechanism, decimal keys arranged in a bank or row, one of said keys being elevated substantially above the remainder to be operated by the palm of the hand of the operator, said key being broad enough to overlie another key in the bank. 100

4. In a decimal-tabulating mechanism, 105 the combination with a carriage and decimal stops therefor, of carriage-releasing mechanism, decimal keys arranged in a bank or row, one of said keys being elevated substantially above the remainder to be operated by the palm of the hand of the operator, said key being broad enough to overlie another key in the bank and being of sufficient elevation above said key to permit the operator to reach under the broadened key 110 to operate the key which is overhung thereby. 115
